ATTORNEY

UNITED STATES PATENT OFFICE.

CHARLES OSBORNE, OF NEW YORK, N. Y., ASSIGNOR TO WHITING MANUFACTURING COMPANY, OF NEW YORK, N. Y., A CORPORATION OF NEW YORK.

DESIGN FOR A HANDLE FOR SPOONS, FORKS, OR SIMILAR ARTICLES.

40,745.

Specification for Design.

Patented June 28, 1910.

Application filed March 10, 1910. Serial No. 548,503. Term of patent 14 years.

To all whom it may concern:

Be it known that I, CHARLES OSBORNE, a citizen of the United States, residing in the city of New York, borough of Manhattan, in the county and State of New York, have invented a new, original, and ornamental Design for Handles for Spoons, Forks, and Similar Articles, of which the following is a specification, reference being had to the accompanying drawings, forming part thereof.

Figure 1 is a view of the obverse face of a spoon showing my new design, with a fork also shown in dotted lines, and Fig. 2 is a corresponding view of the reverse face.

The characteristic feature of my design resides in a raised edge surrounding or following the outline of the handle upon both faces and a dot and spindle ornamentation in relief following this raised edge upon the obverse face, such ornamentation being within and adjacent the raised edge but not

projecting beyond the outer plane thereof. The dot and spindle ornamentation terminates at a point before reaching the bowl of the spoon or the body portion of the fork or similar article, the opposite portions thereof being disconnected and the said ornamentation also terminating at the upper end of the handle upon opposite sides of the transverse portion thereof and between these separated side ornamentations is a leaf or foliate ornamentation which extends over upon the reverse face of the handle and terminates upon such face in a plurality of beads to give an ornamental appearance to said reverse face.

I claim:—

The ornamental design for a handle for a spoon, fork or similar article, as shown.

CHARLES OSBORNE.
